UNITED STATES PATENT OFFICE.

ALVA J. FISHER, OF EVANSTON, ILLINOIS, ASSIGNOR TO HURLEY MACHINE COMPANY,
OF CHICAGO, ILLINOIS, A CORPORATION OF ILLINOIS.

GEARING.

1,115,525.

Specification of Letters Patent.

Patented Nov. 3, 1914.

Application filed March 30, 1912. Serial No. 687,545.

To all whom it may concern:

Be it known that I, ALVA J. FISHER, a citizen of the United States, residing at Evanston, in the county of Cook and State of Illinois, have invented certain new and useful Improvements in Gearing, of which the following is a specification.

My invention relates to a washing machine of the power-driven type employing a continuously running motor for operating both the agitator of the washing machine and the wringer and the object thereof is to provide means for interrupting the operation of the agitator at the will of the operator without stopping either the motor or the connections for driving the wringer and for again bringing the motor and agitator into operative relationship whenever desired.

In the drawings, Figure 1 is a sectional elevation of a portion of a washing machine embodying my invention; Fig. 2 is a section on the line 2—2 of Fig. 1 but on an enlarged scale; Fig. 3 a perspective of one of the clutch members; Fig. 4 a perspective of the agitator shaft pinion and its clutch face or member; Fig. 5 a sectional plan on the line 5—5 of Fig. 1 and Fig. 6 a side elevation of a portion of the driving mechanism.

For the purpose of a disclosure of my invention it is not necessary to illustrate a complete washing machine and its wringer and consequently I have shown only the lower portion of the receptacle 1 which is supported as usual by the legs 2. Moreover, I have not shown the agitator proper but merely the oscillating agitator shaft 3 which extends centrally and vertically through the bottom 1^a of the receptacle. The driving mechanism and connections hereinafter described are all mounted upon and supported by a plate 4 which is secured to the legs 2 with the result that the driving mechanism is substantially contained within the outside lines of the washing machine.

Referring to the power-drive mechanism and connections the prime-mover in the present instance is an electric motor 5 whose extended armature shaft 6 is provided with a small pulley 7 which is operatively connected by means of a pulley 8 with a large pulley 9. This latter pulley is secured to a shaft 10 mounted in suitable bearings 11 on the plate 4 and provided at one end with a pinion 12 which meshes with the large gear

wheel 13. This gear wheel is provided with a crank pin 14 operatively connected by means of the connecting rod or pitman 15 with a reciprocating rack bar 16. This bar operates in the bearings or guides 17 and 18 and its rack teeth 16^a mesh with a pinion 19. As a result of these connections the rotation of the motor causes an oscillation of the pinion 19. The gear wheel 13 is secured to a horizontal shaft 20 mounted in bearings 21, 21 on the base plate 4 and the extended right-hand portion (Figs. 1 and 5) constitutes a part of the driving connections of the reversible driving connections for the wringer. As shown a shifting clutch member 22 is splined upon the shaft 20 so as to move longitudinally thereof and to be rotated thereby. This clutch member is adapted to be operated by means of a clutch shifter 23 and an operating rod 24 connected therewith and extending laterally to one side of the machine. This clutch 22 has on one side a laterally extending lug 22^a and on the other side a similar lug 22^b. The first mentioned lug is adapted to engage and co-operate with a corresponding lug 25^a extending laterally from a sleeve 25 loosely mounted upon the shaft 20. This sleeve has a sprocket wheel 26 which is adapted to drive through the medium of the sprocket chain 27 a similar sprocket wheel 28 secured to a shaft 29 parallel to the shaft 20 and mounted on the base plate 4 in the bearings 30, 30. On the side opposite the clutch 22 of which the sprocket wheel is located, the shaft 20 has loosely mounted upon it a pinion 31 meshing with a similar pinion 32 which is secured to the shaft 29. The outer end of this latter shaft has secured to it a sprocket wheel 33 which through the medium of a sprocket chain 34 is adapted to drive the usual wringer (not shown). When the motor is running the shaft 20 is continuously rotated. When it is desired to operate the wringer in one direction the clutch 22 is moved longitudinally accordingly and in case the same is moved from its neutral position and to the left (Fig. 5) the two lugs 22^a and 25^a will engage with the result that the shaft 29 is rotated by the sprocket wheels and chain and the sprocket wheel 33 is likewise rotated thereby operating the wringer in one direction. At this time the pinions 31 and 32 operate idly. A shifting of the clutch 32 in the opposite di-

rection will cause engagement between the lug 22^b and a lug 31^a projecting laterally from the pinion 31 with the result that the latter pinion will drive the pinion 32 and consequently the shaft 29 and sprocket wheel 33, thereby driving the wringer in the opposite direction.

I do not herein make any claim to the driving connections and the reversing mechanism above described as the same form the subject matter of my prior applications filed on August 22, 1911, Ser. Nos. 645,423 and 645,424.

The agitator shaft 3, hereinbefore referred to, has its lower end mounted in a vertical bearing 35 at whose upper end the pinion 19 is located, the same being arranged to rotate freely upon such shaft. This pinion is provided on its upper side with a clutch face or with one of two clutch members, the same being preferably an integral structure with the pinion as illustrated in Fig. 4. This clutch face or portion indicated at 36 comprises an upward extension or body portion having a series of vertical notches or recesses 36^a in any two opposite ones of which the lugs 37^a of the other clutch member 37 are adapted to engage. The clutch member 37 is the movable one and is secured as by means of the cross pin 38 to the agitator shaft 3. It will be understood that by raising and lowering this agitator shaft the clutch member 37 is correspondingly moved or shifted thus causing a clutching and unclutching action. For operating or shifting the agitator shaft in a vertical direction suitable means under the ready and convenient control of the operator are provided. In the present instance these means comprise the following elements: A collar 39 is secured to the shaft 3 at a point above the clutch member 37 and below the bottom 1^a of the receptacle. This collar is secured in adjustable manner upon the shaft in any suitable way as by means of the set screw 40. The collar is provided with the parallel flanges 39^a which form between them a curved recess which in the present instance is annular and adapted to receive a crank pin 41 projecting eccentrically from the disk 42. This disk is suitably secured to an oscillating operating rod 43 which is mounted in suitable bearings 44 supported from the receptacle. This operating rod extends radially of the receptacle and terminates just beyond the outer line of the body of the receptacle and slightly below the same where it is provided with an operating handle 45 whose operation in one direction or the other determines the direction of movement and the position of the agitator shaft 3. The normal position of the parts is one adapted for clutching action as shown in Figs. 1 and 2 but when it is desired to stop the movement of the agitator

this can be done without stopping the motor and without stopping the main driving connections (including those for operating the wringer) by merely shifting the handle 45 in the proper direction with the result that the shaft 3 is moved vertically thereby detaching or unclutching the clutch member 37 from the clutch face or portion of the pinion 19. This latter pinion will continue to oscillate but such oscillation will not be communicated to the agitator shaft. Thus, only those driving connections directly concerned with the agitator shaft are stopped, leaving running the remainder of the driving connections, so that if desired the wringer may be operated during the period of stoppage of the agitator.

In the practical operation of washing machines of this character it is often desirable to temporarily stop the operation of the agitator without stopping the wringer or its driving connections. By the employment of my invention I am enabled to leave the motor running continually during the entire washing operation and to instantly and conveniently stop the agitator mechanism and to throw it into operation again with equal facility, and also to operate the wringer while the agitator mechanism is stopped.

I claim:

1. The combination of a shaft, a continuously running motor, driving connections from the motor to the shaft including an oscillating pinion, clutch mechanism between such pinion and shaft, and means for operating the clutch mechanism whereby the actuation of the shaft may be interrupted at will without stopping the motor or said mechanism.

2. The combination of a shaft, a continuously running motor, driving connections from the motor to the shaft including an oscillating pinion, which has a clutch face, a movable clutch member mounted upon the shaft and arranged to coöperate with said clutch face, and means for operating said clutch member whereby the actuation of the shaft may be interrupted at will without stopping the motor or said mechanism.

3. The combination of a shaft, a continuously running motor, driving connections from the motor to the shaft including an oscillating pinion mounted to rotate on the shaft, clutch mechanism between such pinion and shaft, and means for operating the clutch mechanism whereby the actuation of the shaft may be interrupted at will without stopping the motor or said mechanism.

4. The combination of a shaft, a continuously running motor, driving connections from the motor to the shaft including an oscillating pinion mounted to rotate on the shaft and having a clutch face, a clutch member coöperating with the clutch face

and secured to the shaft, and means for shifting the shaft and clutch member to unclutch it.

5. The combination of a shaft, a continuously running motor, driving means between the motor and shaft including an oscillating pinion mounted to rotate on the shaft and having a clutch face on its upper side, a clutch member secured to the shaft and normally in clutch with said face, and means for shifting the shaft longitudinally to unclutch said member.

6. The combination of a shaft, a continuously running motor, driving means between the motor and shaft including an oscillating pinion mounted to rotate on the shaft and having a clutch face, a clutch member coöperating with the clutch face and secured to the shaft, a collar secured to the shaft and having a curved recess, a crank pin engaging in said recess, and means for oscillating the pin to raise and lower the shaft.

7. The combination of a shaft, a continu-

ously running motor, driving means between the motor and shaft including an oscillating pinion mounted to rotate on the shaft and having a clutch face, a clutch member coöperating with the clutch face and secured to the shaft, a collar secured to the shaft and having a curved recess, a crank disk, a crank pin thereon adapted to engage in said recess, and an operating device connected with the disk for actuating it.

8. The combination of a shaft, a continuously running motor, driving means between the motor and shaft including an oscillating pinion mounted to rotate on the shaft and having a clutch face, a clutch member coöperating with the clutch face and secured to the shaft, a collar adjustably secured to the shaft, and means operating upon the collar for raising and lowering the same and the shaft.
